RESETTABLE FUSE

Everett P. Larsh, Vandalia, Ohio, assignor to
The Master Electric Company, Dayton, Ohio,
a corporation of Ohio

Application February 6, 1932. Serial No. 591,403

14 Claims. (Cl. 200—124)

The present invention relates to electric fuses or thermally controlled circuit breakers, and more particularly to a resettable fuse which, after having been automatically operated under excessive temperature influence to open an electric circuit, may be manually readjusted to again close the circuit preparatory to another operation.

In its preferred form the device includes a spring actuated contact element held in contacting position against the tension of its actuating spring by a detent means to maintain an electric circuit closed, and having a fusible connection with the operating device, which when fused under excessive heat condition releases the device for automatic movement out of contacting position under influence of the spring thereby opening the circuit. The cooling of the fusible material reunites the detent and operating device in the relation to which they have been moved. The subsequent manual return of the contact device to closed position retensions the spring and readjusts the detent to hold the device in its closed condition until again released by subsequent fusing of the joint. The fusible joint may be subjected to direct heat radiation or may be subject to heat influence through a collector of heat conductive material, or may be operated by the influence of a heater coil normally included in the controlled circuit.

The object of the invention is to simplify the construction as well as the means and mode of operation of such devices whereby they will not only be cheapened in construction, but will be more efficient in operation, automatic in action, uniformly sensitive to thermal conditions, capable of repetitious operation, and unlikely to get out of order.

A further object of the invention is to provide an automatic circuit breaker which will afford minimum resistance in the circuit, and which will respond promptly and with decisive action to an excessive thermal condition.

A further object of the invention is to provide an automatic circuit breaker operable by external thermal conditions.

A further object of the invention is to provide an automatic circuit breaker which will be automatically reconditioned after use.

A further object of the invention is to provide a simple device having few operating parts which may be readjusted to operative condition repeatedly.

With the above primary and other incidental objects in view as will more fully appear in the specification, the invention consists of the fea-

tures of construction, the parts and combinations thereof, and the mode of operation, or their equivalents, as hereinafter described and set forth in the claims.

Referring to the accompanying drawing wherein are shown the preferred, but obviously not the only forms of embodiment of the invention, Fig. 1 is a longitudinal sectional view of the assembled resettable fuse forming the subject matter hereof adapted for operation under external heat conditions. Fig. 2 is a transverse sectional view on line 2—2 of Fig. 1. Fig. 3 is a transverse sectional view on line 3—3 of Fig. 1. Fig. 4 is a longitudinal sectional view of the assembled resettable fuse embodied in a standard type of fuse plug adapted for insertion in an electric circuit as a protection against overload. Fig. 5 shows a plan view. Fig. 6 discloses another modification wherein a ratchet clutch mechanism has been used instead of the friction clutch shown in Fig. 2.

Like parts are indicated by similar characters of reference throughout the several views.

The fuse construction forming the subject matter hereof may be embodied in different forms and applied to numerous purposes of which only two are herein shown and described.

The embodiment of the invention illustrated in Fig. 1 is especially applicable to the control of an electric circuit under influence of surrounding temperature conditions and has been illustrated in its application to a motor housing where in the event the motor should be overheated to predetermined degree the device will operate to open the motor circuit. This is merely an illustrative application and it is to be understood that the device may be positioned in any warm air stream or in proximate relation to any point at which abnormal rise of temperature is likely to occur.

In Fig. 4 the invention is embodied in a safety device for installation in a standard fuse block socket and is operable by overload upon the electric circuit causing the heating of a heater coil embodied within the device. The general construction in both instances is the same.

The device as illustrated in the drawing comprises a tubular shell or casing of dielectric material having an enlarged head 2 and provided with diametrically opposite slots 3—3 for convenience of assembly. Interiorly the casing or shell is formed with two oppositely disposed spaced rabbets or shoulders 4 and 5.

Disposed axially within the casing is a revoluble center post or stem 6 of heat conductive material which is preferably, though not necessarily, metallic tubing. The stem 6 is provided

60

110

with a head 7 preferably of insulating material which is rotatably seated upon the upper shoulder 4 and is provided with a socket 8 within which the upper end of the center post or stem 6 is securely seated. The head 7 is formed with a projecting finger piece 9 engageable alternately with stop lugs 10 upon the casing 1 to limit the to and fro oscillation of the head 7 and stem 6 to a range of approximately ninety degrees.

10 Surrounding the stem 6 beneath the head 7 is a helical spring 11, one end of which is secured to the stem, or to the head by which the stem is carried and the other end of which is secured to the casing. This spring, as will be described, 15 tends to rotate the stem 6 to operate the device from its "on" to its "off" position.

Fixedly mounted upon the casing or shell in diametrically opposite positions are two electrical contact terminals 12-12. In the present instance these contacts comprise metal strips bent into substantially U formation enclosing the lower margin of the casing or shell with one arm extending interiorly thereof and the other arm extending exteriorly and clenched within the correspondingly positioned slots 3-3. Each contact member 12 is provided with a solder lug or connection 13 to which the electrical circuit lead wires are to be attached.

30 Mounted upon the stem 6 are two contact arms 14-14 interconnected with each other and adapted upon rocking motion of the stem to make and break contact with the contact terminals 12. In the preferred construction these arms 14 are carried by a metallic thimble or flanged collar 15 secured to the stem 6 and electrically connecting the arms to each other.

Secured to the stem 6 by a fusible joint 16 of soft solder, wax, or other adherent heat sensitive material subject to softening by fusing action 40 under increased heat condition, is a detent 17 having arresting engagement with the interior of the casing wall. In the illustrated construction this detent comprises an extended spring arm 17 having frictional engagement with the 45 interior of the casing wall immediately beneath the shoulder 5 thereby normally not only holding the stem 6 against rotative movement under influence of the spring 11 but by its engagement beneath the shoulder preventing withdrawal of 50 the head and stem from the casing.

The stem 6 is turned by the head 7 against the tension of the spring 11 to "on" position wherein the contact arms 14 engage with the contacts 12 to close the electrical circuit. It is held in such position of adjustment by the clutch like engagement of the detent arm 17 with the casing 1 under the inherent tension of such detent arm, thereby maintaining the circuit closed and the actuating spring 11 under tension.

60 Vanes 18 of heat conductive material are carried at the lower end of the stem and exposed to the temperature of the surrounding atmosphere. The heat absorbed by the vanes 18 being transmitted through the heat conductive stem 6 to the fusible joint 16 causes the solder, wax or other attachment material to fuse or soften, and its resistance to weaken to sufficient extent that it is overcome by the tension of the spring 11, which thereupon actuates the stem and contact arms 14 through a partial rotation to "off" position breaking the contact between the arms 14 and the contact terminals 12 and opening the electrical circuit.

As the temperature of the surrounding atmosphere decreases, the solder, wax or other

uniting material congeals and reunites the detent arm and stem in their newly assumed relation, preparatory to readjustment into "on" or contacting position.

80 The temperature at which the joint 16 fuses and releases the stem for action under influence of the spring is determined by the character of the fusible material employed for uniting the parts. Solder may be compounded in varying degrees of hardness from an extremely "soft" 85 solder, melting at comparatively low temperature to "hard" solders which are heat resistant to a comparatively high degree. By selecting a solder having a fusing point at the temperature at which it is desired that the device shall operate, such operation can be controlled within a relatively narrow range. If operation at lower temperature is desired, wax may be substituted for solder in making the releasable joint 16.

90 The vanes 18 being heated by contact with surrounding heated atmosphere, the heat is transmitted through the stem to the fusible joint 16, and when the temperature has reached the pre-determined melting point of the solder, the stem 6 is released from the detent 17 by the fusing 95 of the joint 16 and is snapped through decisive rotary motion until arrested by engagement of the finger piece 9 with the stop lugs 10, carrying with it the contact arms 14 and thereby opening the circuit. As the temperature of the parts falls below the melting point of the solder, the 100 detent arm 17 automatically resolders itself to the center post or stem and the device can be manually reset and the circuit again closed by turning the head 7 to "on" position. The device 105 cannot be reset, however, until the overheated condition has been corrected and the temperature has again fallen below the melting point of the solder thus affording positive assurance against continuance of the overheated condition.

110 The line fuse construction illustrated in Fig. 4 is substantially identical with that heretofore described, except that the casing 1 is completely closed at its lower end which is provided with a 115 contact button or terminal 19 to which is connected one end of a heater coil 20. The opposite end of the heater coil 20 is attached to one of the contact terminals 12. The other terminal 12 is attached to a screw threaded metal 120 jacket 21 exteriorly enclosing the casing 1 and adapted for engagement in a standard fuse plug socket. The heater coil 20, being thus directly included in the electrical circuit, as are also the contact arms 14, becomes heated in event of an 125 overload upon the circuit and the heat generated within the chamber of the casing effects release of the fusible joint 16, thereby releasing the stem and contact arms 14 for movement to "off" position under influence of the tensioned spring 130 11 as before described.

135 While a spring arm having frictional clutch or braking action upon the interior of the casing is quite effective and practical such detent may be of a pawl and ratchet type as illustrated 140 in Fig. 6 wherein a detent pawl 22 carried by the stem 6 has engagement with ratchet teeth 23 formed interiorly of the casing to hold the stem in its adjusted position against the tension of its spring.

145 While as heretofore described the device is operable under excessive temperature conditions to open the circuit, it will be understood that without any change of construction or operation other than differently positioning the con-

tact arms 14 upon the stem 6 whereby they assume "off" positions relative to the contacts 12 when the spring 11 is under tension in which they are held by the detent 17, the device may be 5 made operative to close the circuit under excessive thermal condition and thereby energize an alarm, release a sprinkler system, operate a control device or perform other function.

Therefore such reversely operating construction, which forms a part of the present invention, shall be deemed included within the scope of the hereinafter stated claims wherein "closed position" refers to the operated position to which the parts are moved under influence of the 10 spring, and "open position" refers to the normal position in which the parts are held by the detent against spring tension.

From the above description it will be apparent that there is thus provided a device of the character described possessing the particular features of advantage before enumerated as desirable, but which obviously is susceptible of modification in its form, proportions, detail construction and arrangement of parts without departing from the 15 principle involved or sacrificing any of its advantages.

While in order to comply with the statute the invention has been described in language more or less specific as to structural features, it is 20 to be understood that the invention is not limited to the specific features shown, but that the means and construction herein disclosed comprise the preferred form of several modes of putting the invention into effect, and the invention is 25 therefore claimed in any of its forms or modifications within the legitimate and valid scope of the appended claims.

Having thus described my invention, I claim:

1. A resettable fuse, including a casing, spaced 40 electrical contacts in the casing, a rotatable center post, diametrically disposed electrical contacts carried by the post and moved into and out of bridging contact with the first mentioned contacts by a partial rotation of the post, an actuating spring tending to rotate the post to shift the contacts to off position, friction clutch means normally holding the post and contacts against movement under influence of the spring, a fusible connection between the post and clutch adapted 45 to release the post from the clutch means under influence of abnormal temperature condition, for rotative action to inoperative position, said fusible connection being automatically re-established in the operated position of the center 50 post to again interconnect the post and clutch whereby upon return of the post and contacts to their original operative positions the clutch 55 will maintain them in such adjusted position until again released by fusing of the fusible connection.

2. In a resettable fuse plug, a shell-like housing having therein a pair of relatively fixed electrical contacts, a movable member within the housing, a pair of contact members carried thereby and movable into and out of engagement with the first contact by adjustment of the movable member, an actuating spring therefor tensioned when the contacts are in engagement for automatically adjusting the movable member to break the electrical contact of said contact members, a detent normally holding the movable member against movement under influence of the spring, a fusible connection between the detent and the movable member automatically released under influence of abnormal temperature conditions

to permit disengagement of the contacts under influence of the spring, said fusible connection being automatically re-established upon the return of normal temperature conditions, whereupon the movable member and contact carried thereby may be manually re-adjusted to normal operative position preparatory to subsequent automatic release.

3. In a construction of the character described, a shell-like housing, a central rock post therein, means for limiting the rocking motion of the post to predetermined degree, a pair of electrical contacts carried by the housing, complementary electrical contacts carried by the rock post and moved into and out of operative relation with the first contacts by the rocking action of the post, a helical spring normally under tension and tending to rock the post to open the electrical connection between the contacts, a detent member carried by the post and having operative engagement with the housing and resisting the actuating influence of the spring, and a fusible joint between the detent and the post fused by abnormal temperature conditions to disconnect the post and detent and permit the post and electrical contact carried thereby to move to inoperative position under influence of the spring, the joint between the post and detent being automatically re-established upon return of normal temperature condition.

4. In a device of the character described, the combination with a make and break electric switch and actuating means normally tending to open the switch, of a rock stem therefor, a detent arm carried by the stem normally holding the switch against opening movement, and a fusible joint between the rock stem and the detent arm adapted to be fused by abnormal temperature condition to automatically release the switch for opening action, the joint being automatically re-established upon the return of normal temperature condition preparatory to manual resetting of the switch in closed condition.

5. In a device of the character described, the combination with a make and break electric switch and actuating means normally tending to open the switch, of a rock stem therefor, a housing enclosing the operating parts, a detent member having frictional engagement with the interior wall of the housing to hold the stem and contact against opening movement, a fusible joint between the detent member and stem automatically releasing the parts upon abnormal increase of temperature thereby permitting movement of the stem and switch to inoperative positions, the joint being automatically re-established upon the cooling of the parts.

6. In a device of the character described, the combination with a make and break electric switch and actuating means normally tending to open the switch, a detent member normally connected with the movable element of the switch and operative to retain the switch in closed condition against the influence of its actuating means, a fusible joint intermediate the detent member and the movable switch element with which the detent is connected, said joint being fused by abnormal increase of temperature to release the switch element for movement to inoperative position said joint being automatically re-established upon the cooling of the parts preparatory to succeeding operation and manually operable means for returning the switch to closed condition.

7. In a device of the character described, the

- combination with a make and break electric switch and actuating means normally tending to open the switch, a detent member normally connected with the movable element of the switch and operative to retain the switch in closed condition against the influence of its actuating means, a fusible joint intermediate the detent member and the movable switch element with which the detent is connected, said joint being fused by abnormal increase of temperature to release the switch element for movement to inoperative position, said joint being automatically re-established upon the cooling of the parts preparatory to succeeding operation, a heat conductive member associated with the fusibly joined parts by which the fusible joint is subjected to external temperature conditions, and manually operable means for returning the switch to closed condition.
8. In a device of the character described, the combination with a make and break electric switch and actuating means normally tending to open the switch, a detent member normally connected with the movable element of the switch and operative to retain the switch in closed condition against the influence of its actuating means, a fusible joint intermediate the detent member and the movable switch element with which the detent is connected, said joint being fused by abnormal increase of temperature to release the switch element for movement to inoperative position, said joint being automatically re-established upon the cooling of the parts preparatory to succeeding operation, a heat transmitting element subjecting the fusible joint to proximate temperature conditions, and manual means for resetting the switch in closed condition.
9. In a device of the character described, the combination with a make and break electric switch and actuating means normally tending to open the switch, a detent member normally connected with the movable element of the switch and operative to retain the switch in closed condition against the influence of its actuating means, a fusible joint intermediate the detent member and the movable switch element with which the detent is connected, said joint being fused by abnormal increase of temperature to release the switch element for movement to inoperative position, said joint being automatically re-established upon the cooling of the parts preparatory to succeeding operation, a heat radiating element in proximate relation with the operating parts by which the fusible joint is subjected to increased temperature influence, and manual means for returning the switch to operative position.
10. In a device of the character described, the combination with a make and break electric switch and actuating means normally tending to open the switch, a detent member normally connected with the movable element of the switch and operative to retain the switch in closed condition against the influence of its actuating means, a fusible joint intermediate the detent member and the movable switch element with which the detent is connected, said joint being fused by abnormal increase of temperature to release the switch element for movement to inoperative position, said joint being automatically re-established upon the cooling of the parts preparatory to succeeding operation, a heat conductive member associated with the fusibly joined parts by which the fusible joint is subjected to external temperature conditions, and manually operable means for returning the switch to closed condition.
11. In a construction of the character described, a make and break electric switch and actuating means tending to open the switch of a housing therefor, a rock stem for the movable switch element, a spring arm carried by the stem having frictional contact with the interior wall of the housing to hold the movable switch element in closed position and a fusible joint between the spring arm and stem automatically releasing the switch element under abnormal increase of temperature, the joint being re-established upon cooling of the parts preparatory to return of the switch element to closed position.
12. In a construction of the character described, a make and break electric switch and actuating means tending to open the switch of a housing therefor, a rock stem for the movable switch element, a detent member having operative engagement with the interior of the housing to maintain the movable switch element in closing position, a fusible joint intermediate the detent and switch element adapted upon abnormal increase of temperature to release the switch element and permit its movement to inoperative position, the joint being automatically re-established upon cooling of the parts preparatory to return of the switch to closed position.
13. In a circuit interrupter, a support, a rotatably mounted member carried in said support and a detent engaging said support and fusibly attached to the rotatable member, normally preventing rotation thereof.
14. In a circuit interrupter, a cylindrical support, a member mounted for rotation therein and a member frictionally engaging said support and fusibly attached to the first member normally preventing rotation thereof.
